UNITED STATES PATENT OFFICE.

WILLIAM DONALD, OF GLASGOW, SCOTLAND.

STEAM BOILER AND EVAPORATOR.

Application filed December 9, 1925, Serial No. 74,403, and in Great Britain December 17, 1924.

This invention has reference to steam boilers and evaporators, and has particular reference to boilers or evaporators of the horizontal fire-tube type, that are provided with a multiplicity of fire-tubes extending longitudinally therethrough for the passage of gaseous products of combustion.

My invention has for its object to provide a boiler of the type set forth whereby the contents thereof can be more uniformly and quickly heated.

A further object of my invention is to provide an improved construction and arrangement of firing chambers and smoke boxes.

A further object is to enable the firing tubes to be easily and quickly cleaned.

A further object is to provide an improved construction of fire tubes.

A still further object of my invention is to provide an auxiliary boiler or boilers to be heated by waste heat.

Those and other improvements will be hereinafter described and pointed out in the claims.

According to my invention, horizontal fire tube boilers or evaporators, hereinafter referred to as boilers, are provided at each end thereof with gas burners, fireboxes or furnaces or are otherwise adapted to be fired at both ends simultaneously, so that the gaseous products of combustion entering the fire tubes at each end traverse the complete length of the boiler.

According to one embodiment of my invention a boiler or evaporator, hereinafter referred to as a boiler, is provided with a smoke box at each end thereof, tubes extending from the outer tube plate of each smoke box, through the corresponding boxes, through the boiler or evaporator, and terminating in the other smoke box, and gas burners, furnaces or the like provided to direct hot gaseous products of combustion into the exposed ends of said fire tubes and suction draught pipes attached to each smoke box by means of which gaseous products of combustion are drawn from each end of the boiler simultaneously and travel in opposite directions through the boiler or evaporator to the smoke box at the other end thereof.

The said smoke boxes may be separated

from the boiler ends and the gas burners or the like located in the firing chambers formed between the boiler ends and smoke boxes, the fire tubes extending from each end tube plate of the boiler, through the boiler and through the said chambers to the corresponding smoke box.

By such construction the hottest part of the fire tubes is located within the boiler and not within the smoke box.

If desired an auxiliary boiler or heater may be provided at one or both ends of the boiler and between said firing chambers and the corresponding smoke box, the fire tubes being extended through, or provided with extensions extending through said auxiliary boiler or heater, or boilers or heaters, and terminating in the corresponding smoke box.

To facilitate the cleaning of the fire tubes, spy holes are provided in the outer plate of the smoke boxes and directly in line with the ends of the tubes which terminate therein, said holes being provided with movable covers.

By such arrangement a suitable tool can be inserted through the spy holes and through the fire tubes to remove the deposits in the interior thereof.

My invention further consists in features of construction which will be hereinafter described and pointed out in the claims.

In order that my invention will be properly understood I have hereunto appended six explanatory sheets of drawings and whereon:

Figure 1 illustrates one construction of boiler in accordance with my invention.

Figure 2 is a plan view, and

Figure 3 illustrates an end elevation of the boiler showing two arrangements of gas burners.

Figures 4 and 5 illustrate views corresponding to Figures 1 and 2 respectively of a boiler with smoke boxes separated from the boiler ends and gas burners located within the firing chambers between the boiler ends and smoke boxes.

Figure 6 is a sectional elevation on the line 6—6 Figure 4.

Figures 7 and 8 illustrate elevation and plan respectively and Figure 9 is a sectional end elevation on the line 9—9 Figure 7, of a boiler in accordance with my invention and

provided with auxiliary boilers at the ends thereof, located between the firing chambers and smoke boxes.

Figure 10 illustrates in section two fire tubes and stay rod as provided in the boiler shown in Figures 1, 2 and 3.

Figure 11 illustrates two fire tubes provided in the boiler shown in Figures 4, 5 and 6.

Figure 12 illustrates two of the fire tubes provided in the boiler shown in Figures 7, 8 and 9.

Figure 13 illustrates a portion of one end tube plate of the boiler illustrated in Figure 4.

Figure 14 is a section through the said plate showing the firing ends of the tubes which terminate therein.

Figure 15 illustrates the manner in which the ends of the other tubes which pass through said plate are secured in position.

Figures 16, 17 and 18 illustrate views corresponding to Figures 13, 14 and 15 respectively of the tube plate and tubes shown in Figure 7.

Figure 19 is a plan view of two fire tubes corresponding to those shown in Figure 11 and showing the boiler including the smoke boxes thereof.

Figure 20 shows the tube in section with helical worm located therein, and with winding handle attached thereto.

Figure 21 shows to a larger scale the junction end of the helical worm shaft and boss of operating handle.

Throughout the drawings the same reference letters denote the same or corresponding parts.

Referring to the drawings:—

40 a denotes the boiler shell, a^1 and a^2 the end tube plates, b^1 and b^2 the smoke boxes, d the gas burners, e control cocks for the latter and f the gas main or gas supply pipes.

45 In the boiler illustrated in Figures 1 to 3 the smoke boxes are located directly at the ends of the boiler, the tube plates of the latter also constituting the inner tube plates of the smoke boxes, and the boiler shell also constituting the shell of the smoke boxes.

50 The fire tubes employed in this apparatus are illustrated in Figure 10 from which it will be seen that each tube comprises a tube extending longitudinally through the boiler between the two tube plates a^1 and a^2 and shorter extensions which extend through the smoke boxes.

55 Substantially half the tubes c^3 are secured at one end in corresponding holes in the tube plate a^1 by nuts l and their other ends, which are expanded, are secured by a nut l^1 in corresponding holes in the tube plate a^2 .

60 Inserted in said expanded ends are the shorter tubes c^4 which extend through the smoke box b^2 to the outer tube plate b^4 , the

65 ends of said smaller tubes being likewise expanded to receive a ferrule c^5 .

The remaining fire tubes c^1 are secured by nuts l^2 in corresponding holes in the tube plate a^2 , extend longitudinally through the boiler to the tube plate a^1 and their expanded ends secured in corresponding holes in the latter plate by means of the nuts l^3 . Shorter tubes c^2 inserted in said expanded ends extend through the smoke box to the outer tube plate b^3 , their outer ends thereof being provided likewise with ferrules c^6 .

70 The burners d are located in alignment with the outer ends of said shorter tubes at each end of the boiler.

75 Connected to the smoke boxes b^1 and b^2 are two pipes g which terminate in a pipe h connected to any suitable source of suction.

The burners shown in this arrangement are arranged in two series, the one vertical and the other horizontal as clearly shown in Figure 3 but may be all arranged vertically, horizontally or otherwise.

80 The boiler is also provided with the usual boiler fittings including a pressure gauge j , relief valve k , feed water pipe s , and steam outlet pipes.

85 It will be noted that the pipes are all located in the lower portion or half of the boiler while stays m extend between the boiler tube plates in the upper part thereof.

90 In operation the hot gases of combustion from the burners at each end of the boiler enter substantially half the tubes at each end and pass in two series of tubes in opposite directions through the boiler to the smoke boxes at the opposite ends and thereafter are drawn through the pipes g and h by suction draught. By such arrangement the liquid in the boiler is heated substantially uniformly throughout the boiler.

95 In Figures 4 to 6 the smoke boxes b^1 and b^2 are separated from the ends of boiler and a firing chamber d^1 and d^2 formed between the end tube plates a^1 and a^2 of the boiler and the tube plates b^5 and b^6 of the smoke boxes respectively.

100 Located within those chambers and adjacent to the tube plates a^1 and a^2 are the gas burners d .

105 The tubes for this boiler are illustrated in Figure 11.

110 Substantially half the tubes d^8 extend from the tube plate a^1 , through the boiler, through corresponding holes in the tube plate a^2 , the ends being screw threaded at d^7 and secured in position by means of nuts d^8 . Secured to the screw threaded ends by means of coupling nuts d^9 are shorter tubes d^4 which extend across the chamber d^2 and are secured at the other end by means of coupling nuts d^{10} to short screw threaded tubes d^{11} secured in the tube plate b^6 by means of nuts.

The other tubes d^5 are exactly similar but extend from the tube plate a^2 to the tube plate a^1 being screw threaded and secured in position by nuts and connected by coupling nuts with the tubes d^3 which extend across the firing chamber d^1 , the other ends of said tube being likewise secured to short screw threaded tubes d^{12} which are secured within tube plate b^3 of the smoke box b^2 .

10 The ends of the tubes which terminate in the tube plates a^1 and a^2 are expanded and secured in position by nuts d^{13} and are provided with ferrules d^{14} the burners d being located directly in alignment with said tube ends.

15 A similar arrangement of pipes is provided for drawing the gases through the tubes to the smoke boxes and for withdrawing the waste gases from the smoke boxes as is shown in Figures 1 to 3.

20 The operation of this boiler is similar to that already described, that is the hot gaseous products of combustion are drawn by suction from the burners at each end of the boiler simultaneously and travel in opposite directions through the fire tubes to the smoke boxes at the other end, but, by reason of the burners being located adjacent to the end tube plates of the boiler, the hot 25 test part of the tubes is within the boiler and not within the smoke boxes as in the previously described apparatus.

25 In Figures 7, 8 and 9 the boiler illustrated is substantially similar to that illustrated in Figures 4, 5 and 6 with the exception that an auxiliary boiler a^3 and a^4 is located between each of the firing chambers d^1 and d^2 and the corresponding smoke boxes b^1 and b^2 respectively, and the fire tubes or extensions thereof extend through the firing chamber and through the corresponding auxiliary boiler and terminate in the corresponding smoke box.

30 The fire tubes for such boiler are illustrated in Figure 12 and which it will be noted are exactly similar to that shown in Figure 11 with the exception that to the screw threaded tubes d^{11} and d^{12} are coupled extension tubes d^{15} and d^{16} respectively which extend through the auxiliary boilers a^3 and a^4 respectively and which are coupled to short screw threaded tubes d^{17} and d^{18} secured by nuts to the tube plate of the smoke boxes.

35 The operation of this boiler is exactly similar to that described with reference to Figures 4, 5 and 6 with the exception that liquid in the auxiliary boilers is also simultaneously heated by the gases traversing the tubes which pass therethrough.

40 If desired only one auxiliary boiler may be provided.

45 The water heated in the auxiliary boiler or boilers may be employed to heat the feed water for the main boiler or other purpose.

To enable the fire tubes in the boiler to be cleaned I provide the outer plate of the smoke boxes with a series of spy holes and movable covers therefor located directly in alignment with the ends of the tubes which terminate therein.

50 When used as an evaporator the valves controlling the outlet can be operated so that evaporating takes place at any desired pressure and corresponding temperature. It will be understood that by evaporating I also include distilling.

55 Preferably as illustrated in Figures 19, 20 and 21 I provide the fire tubes with helical worms z located therein and which serve the double function of (1) baffling the gases traversing same and (2) serve as a means for cleaning the tubes.

60 Said helical worms are operated intermittently or substantially continuously for the purpose of removing carbonaceous deposits from the interior of the tubes. The rotation of the worms is conveniently effected by moving the cover plate clear of the corresponding spyholes and inserting the boss 65 end of an operating handle z^1 therein.

65 The said boss is internally threaded to receive a corresponding thread on the end of the shaft of the helical worm and is further provided with a short external helix z^2 70 which constitutes a continuation of the helix of the worm. By such arrangement while the helical worm is being rotated to remove the said deposits the passages of the gases of combustion through the tubes is not interrupted.

75 It will be seen on reference to the drawings that all the fire tubes are substantially equally distributed in the lower half of the boiler and further that the tubes which terminate in each smoke box are likewise equally distributed on both sides of the vertical centre line of the boiler. Furnaces may be utilized instead of burners.

80 What I claim is:—

1. An apparatus for steam raising, boiling and evaporating liquids comprising a horizontal boiler, fire tubes extending longitudinally therethrough, smoke boxes at each end of the boiler, firing chambers located intermediate between the boiler ends and smoke boxes, substantially half of said tubes extending from the firing chamber at one end of the boiler to the smoke box at the other end thereof, and the remainder of the fire tubes extending from the other firing chamber to the smoke box at the other end of the boiler, and burners located in both firing chambers to simultaneously supply heat to the fire tubes which terminate therein.

120 2. An apparatus for steam raising, boiling and evaporating liquids comprising a horizontal boiler, fire tubes extending longitudinally therethrough, smoke boxes at each 125

end of the boiler, firing chambers located intermediate between the boiler ends and smoke boxes, substantially half of said tubes extending from the firing chamber at one end of the boiler to the smoke box at the other end thereof, and the remainder of the fire tubes extending from the other firing chamber to the smoke box at the other end of the boiler, burners located in both firing chambers to simultaneously supply heat to the fire tubes which terminate therein, and a source of suction to draw the products of combustion from each end of the boiler simultaneously in opposite directions through the fire tubes to the smoke boxes at the opposite ends of the boiler.

3. An apparatus for steam raising, boiling and evaporating liquids comprising a horizontal boiler, fire tubes extending longitudinally therethrough, smoke boxes at each end of the boiler, firing chambers located intermediate between the boiler ends and smoke boxes, extension tubes extending from substantially half of said tubes at one end of the boiler through the corresponding firing chamber and terminating in the corresponding smoke box, extension tubes extending from the remainder of the fire tubes through the other firing chamber and terminating in the corresponding smoke box, burners located in both firing chambers to supply heat to the fire tubes which terminate therein, and a source of suction to cause the gaseous products of combustion from said burners to travel from each end of the boiler simultaneously in opposite directions through the fire tubes to the smoke boxes at opposite ends of the boiler.

4. An apparatus for steam raising, boiling and evaporating liquids comprising a horizontal boiler, fire tubes extending longitudinally therethrough, smoke boxes at each end of the boiler, firing chambers located intermediate between the boiler ends and smoke boxes, extension tubes extending from substantially half of said tubes, through the firing chamber at one end of the boiler and terminating in the corresponding smoke box, extension tubes extending from the remainder of the fire tubes, through the other firing chamber and terminating in the smoke box at the other end of the boiler, burners located in the firing chambers at each end of the boiler, to supply heat to the tubes which terminate therein and suction means to simultaneously draw the gaseous products of combustion from each end of the boiler through the boiler in opposite directions to the smoke boxes at the opposite ends of the boiler.

5. An apparatus for steam raising, boiling and evaporating liquids comprising a horizontal boiler, fire tubes extending longitudinally therethrough, smoke boxes at each end of the boiler, firing chambers located

intermediate between the boiler ends and smoke boxes, extension tubes extending from substantially half of said tubes, through the firing chamber at one end of the boiler and terminating in the corresponding smoke box, extension tubes extending from the remainder of the fire tubes, through the other firing chamber and terminating in the smoke box at the other end of the boiler, ferrules inserted in the ends of the tubes which terminate in the fire tubes and burners located in the firing chamber to simultaneously direct gaseous products of combustion into the ferrules at both ends of the boiler, and a source of suction to cause the said gases to travel from each end of the boiler in opposite directions through the boiler to the smoke boxes at the opposite ends thereof.

6. An apparatus for steam raising, boiling and evaporating liquids comprising a horizontal boiler, smoke boxes at each end thereof, firing chambers located between said smoke boxes and the boiler ends, an auxiliary boiler located between one of said firing chambers and corresponding smoke box, fire tubes extending from one of said firing chambers through the boiler and through the firing chamber and auxiliary boiler to the smoke box at the other end of the boiler, a substantially similar number of fire tubes extending from the other end of said firing chambers, through the boiler through the firing chamber at the other end and terminating in the other smoke box, burners located in the firing chambers at each end of the boiler and in alignment with the fire tubes terminating in said chambers and a source of suction to cause the gaseous products of combustion to travel simultaneously from each end of the boiler in opposite directions through the fire tubes from the burners to the smoke boxes at the opposite end.

7. An apparatus for steam raising, boiling and evaporating liquids comprising a horizontal boiler, smoke boxes at each end thereof, firing chambers located intermediate between the boiler ends and smoke boxes, auxiliary boilers located between both smoke boxes and firing chambers, fire tubes extending from a firing chamber at one end of the boiler, through the boiler and firing chamber and auxiliary boiler at the other end of the boiler and terminating in the corresponding smoke box, a substantially equal number of fire tubes extending from the other of said firing chambers through the boiler and firing chamber and auxiliary boiler at the other end of the boiler and terminating in the corresponding smoke box, burners located in the firing chambers at each end of the boiler and in alignment with the fire tubes terminating in said chambers and a source of suction to cause the gaseous products of combustion to travel simultaneously from each end of the boiler in

opposite directions through the fire tubes from the burners to the smoke boxes at the opposite end.

8. An apparatus for steam raising, boiling and evaporating liquids comprising a horizontal boiler, fire tubes extending longitudinally therethrough, smoke boxes at each end of the boiler, firing chambers located intermediate between the boiler ends and smoke boxes, substantially half of said tubes extending from the firing chamber at one end of the boiler to the smoke box at the other end thereof, and the remainder of the

fire tubes extending from the other firing chamber to the smoke box at the other end of the boiler, burners located in both firing chambers to simultaneously supply heat to the fire tubes which terminate therein, rotatable helical worms located in said tubes and a source of suction to draw the products of combustion from each end of the boiler simultaneously in opposite directions through the fire tubes to the smoke boxes at each end of the boiler. 15 20

WM. DONALD.
